UNITED STATES PATENT OFFICE.

HERBERT T. BALLARD, OF NORRISTOWN, PENNSYLVANIA.

DESIGN FOR A KNITTED FABRIC.

Application filed September 21, 1921. Serial No. 502,305. Term of patent 7 years.

To all whom it may concern:

Be it known that I, HERBERT T. BALLARD, a subject of the King of Great Britain, residing at Norristown, in the county of Montgomery and State of Pennsylvania, have invented a new, original, and ornamental Design for Knitted Fabric, of which the following is a specification, reference being had to the accompanying drawing, forming part thereof.

The figure is a face view of the knitted fabric.

I claim:

The ornamental design for a knitted fabric, as shown.

HERBERT T. BALLARD.
